UNITED STATES PATENT OFFICE.

ASA HILL MOSHER, OF WESTFIELD, NEW JERSEY.

SAFETY HAIR-PIN

SPECIFICATION forming part of Letters Patent No. 720,601, dated February 17, 1903.

Application filed March 22, 1902. Serial No. 99,467. (No model.)

To all whom it may concern:

Be it known that I, ASA HILL MOSHER, a citizen of the United States, residing at Westfield, in the county of Union and State of New Jersey, have invented a new and useful Safety Hair-Pin, of which the following is a specification.

This invention relates generally to hair-pins, and more particularly to a safety hair-pin, the object of the invention being to provide a device which can be inserted into the hair the same as an ordinary hair-pin and then locked therein, so as to prevent the hair-pin working loose, as commonly occurs with hair-pins now in use.

With these objects in view the invention consists, essentially, in providing a U-shaped hair-pin with a spring-metal fastening device which can be completely withdrawn into the pin for the purpose of inserting the hair-pin into the hair and can then be projected outwardly beyond the pin for the purpose of engaging the hair and preventing the pin working loose.

The invention consists also in certain details of construction hereinafter fully described, and pointed out in the claim.

In the drawings forming a part of this specification, Figure 1 is a perspective view of a safety hair-pin constructed in accordance with my invention. Fig. 2 is an enlarged detail view, partly in section and partly in elevation, illustrating the construction and arrangement of the locking member. Fig. 3 is a detail side elevation, partly in section, showing the parts in the same position as they occupy in Figs. 1 and 2. Fig. 4 is an enlarged detail, partly in elevation and partly in section, showing the position the parts occupy when the locking member is forced into the pin prior to introducing the pin into the hair. Figs. 5 and 6 are detail views showing the openings produced in the hair-pin.

In carrying out my invention I employ a hair-pin A, essentially U-shaped and preferably constructed of tubular material. This hair-pin A has openings A' produced in the front of each member near the bow or head of the pin, the lower edges A² of these openings being abrupt, as most clearly shown in Figs. 5 and 6, the purpose of which will ap-

pear hereinafter. Openings A³ are also produced in the outer sides of each member of the pin, the said openings being produced a short distance above the center of the pin. 55 A spring-metal fastening member is arranged for coöperation with the hair-pin, the said spring-metal fastening member being preferably constructed of a fine piece of spring-wire B, bent, essentially, in the same form as the hair-pin, the members B' being arranged parallel and substantially the same distance apart as the members of the pin A. The lower ends of the members B' are bent back upon themselves, as shown at B², crossing the 65 members at B³, and are curved outwardly, as shown at B⁴. The wire is bent in this manner before being connected to the pin, and in order to connect the said wire to the pin, ends B³ are introduced into the openings A' and the 70 spring-metal fastening member forced down into the pin, each member B' passing down the tubular leg of the pin, and when the wire has been forced down as far as it will go the head or bow portion will rest against the abrupt side 75 A² of the opening A'. When the fastening member is in this position, the ends or prongs will be completely retained within the pin, and the pin can then be introduced into the hair. After the pin has been placed in the hair the 80 head or bow portion of the fastening member is drawn upwardly, and the prongs or outwardly-curved ends B⁴ will be projected through the side openings A³, producing laterally-projecting prongs at each side of the hair-pin, 85 which serve to retain the pin in its proper position and prevent it working loose in the hair. It will also be noted by reference to Fig. 4 that the cross-piece or bowed portion of the pin will contact with the hair as the 90 hair-pin is pushed into the hair, and this contact with the hair will in itself force the bowed portion of the pin outwardly, and thereby project the prongs out of the pin proper at each side. When it is desired to remove 95 the hair-pin, the fastening member is again forced into the pin, as shown in Fig. 4, and the pin can then be removed the same as the ordinary hair-pin.

The simplicity of the device renders it cheap 100 and easy of both construction and manipulation.

Having thus fully described my invention, what I claim as new, and desire to secure by Letters Patent of the United States, is—

In a hair-pin, the combination with the tubular members having a plurality of perforations, of a wire member inserted in the upper perforations, its ends extending downwardly in said tubular members, respectively, then bent back upon themselves bearing against the sides of the tubular members opposite the sides containing the lower perforations, and then crossed over to the said op-

posite side, said ends resting when in their lowermost position immediately below said lower perforations and adapted to be projected through them when the wire member is drawn upward and to be held in either position by the frictional contact of the bent portions with the sides of the tubular members. 15

ASA HILL MOSHER.
